Fig. 1

Fig. 2

Fig. 3

Fig. 4

FIG. 1 is an isometric view of one modification of the invention, FIG. 2 is a side elevation of the invention, and FIG. 3 is an end elevation of the invention. The other side and other end are substantially the same as the side and end shown. FIG. 4 is an isometric view of a specific, preferred form of the invention in which the shading indicates contrasting color. The ends and side walls of the modification of FIG. 4 are, except for the contrasting color, the same as shown in FIGS. 2 and 3. The center roof panels are shown as being translucent or transparent.

I claim:

The ornamental design for a comfort station, substantially as shown and described.
